UNITED STATES PATENT OFFICE.

HARRISON J. L. FRANK, OF DETROIT, MICHIGAN.

KNIFE-BLADE SWITCH.

1,303,284.

Specification of Letters Patent. Patented May 13. 1919.

Application filed August 7, 1918. Serial No. 248,676.

To all whom it may concern:

Be it known that I, HARRISON J. L. FRANK, a citizen of the United States, and residing at Detroit, in the county of Wayne and State of Michigan, have invented a new and Improved Knife-Blade Switch, of which the following is a specification.

This invention relates to the construction of the supports or clips of knife-blade switches, and its object is to provide identical supports and clips of a good-conducting metal which shall be resiliently held in proper adjustment to receive the switch-blades, and which may be used as either supports or as clips as may be desired so that the blades may be reversed when desired.

This invention consists in a support or clip provided with parallel jaws between which the switch-blade may be inserted, the jaws being provided with alined holes to receive a rivet, and a spring mounted intermediate its ends on the rivet outside of one of the jaws, one end of the spring normally pressing against the free end of the 25 jaw on which it is mounted, and the other end of the spring being provided with fingers to prevent the spring from turning on its rivet. It further consists in forming the spring and the jaws with alined holes to receive a screw on which the switch-blade 30 may be mounted when the device is to be used as a support, the screw also determining the pressure between the jaws and the blades, the screw being omitted when the 35 device is to be used as a clip. It also consists in forming a projection on this spring adjacent the screw-hole, which projection enters one or another of the notches formed in the bearing face of the screw head, where- 40 by the screw may be held at any desired adjustment. It also consists in the details of construction illustrated in the accompanying drawing and particularly pointed out in the claims.

45 In the drawing, Figure 1 is a plan of a knife-blade switch having three blades. Fig. 2 is a side elevation thereof. Fig. 3 is an elevation of one of the supports. Fig. 4 is a section on the line 4—4 of Fig. 3. Fig. 5 is a 50 plan of a blank for the tensioning spring for the jaws of the support. Fig. 6 is a section on the line 6—6 of Fig. 3.

Similar reference characters refer to like parts throughout the several views.

55 The base 1 of the switch shown is preferably of slate, marble or other good insu-

lating material and to it are secured the clamps 2 for the usual fuses 3. The screws 4 serve as terminals in the usual manner. A cross bar 5 of good insulating material carries a handle 6 and to this bar may be secured any number of blades 7. These blades are each pivoted on a screw 8 which extends through a smooth hole in the jaw 9 and through a threaded hole in the jaw 10 of a support 11 which is bent up from a strip of good conducting metal, such as hard copper, and which also has considerable stiffness and resilience.

The supports 11 are duplicates of the 70 clips 13 between whose jaws the blades are forced to close the circuits between the screws 4 and the screws 14 which are carried by short bars 15 secured to the base by means of screws 16 that extend through the holes 75 17 in the supports 11. Similar screws extend through similar holes in the clamps 2 and the clips 13 into threaded holes in the short bars 18 to hold the clamps and clips in position.

80 Each clip 13 is provided with a rivet 19 which passes through the jaws 9 and 10 and through a hole 20 in a small plate 22 of spring-metal formed with ears 23 that may be bent around the edges of the jaw 9, as 85 shown in Figs. 3 and 4. This spring plate being held in position by the heads of the rivet insures a predetermined pressure between the jaws 9 and 10 and the blade 7 when the latter is forced in between the jaws 90 of a clip. The upper end of this spring is cupped to bear along its edge against the outer face of the jaw 9, and is formed with a small tooth 24 that enters the notches 25 in the bearing face of the head 26 of the 95 pivot screw 8. A nut 27 may be screwed onto the outer end of the screw 8 to lock it in position and also to relieve the metal of the jaw 10 from the stress of the screw.

90 One of the jaws of each support and clip 100 is preferably formed with a small inwardly-extending projection 28 to limit the movement of the blade between the jaws when the device is used as a clip. The location of this projection is such that the switch-blade 105 will be prevented from striking the rivet 19 which can therefore always move freely and will not be battered up by the switch-blade. As the clips and supports are identical the screws 8 and blades 7 may be removed from 110 one set and mounted on the other so that without any adjustments or additions of

parts the base may be mounted against a wall with the fuses at the top or bottom of the base and the switch will still comply with such regulations as provide for the blades swinging out and down when the switch is opened.

I claim:

1. A switch clip having a pair of jaws adapted to receive a switch-blade between them, a spring plate on the outer side of one of the jaws, said jaws and spring having alined holes intermediate their ends, a rivet extending through said holes, said spring having ears engaging the adjacent jaw to prevent the spring from turning on the rivet, said jaws and spring also having another set of alined holes nearer their free ends, and a screw extending through said holes to receive a switch-blade.
2. A switch clip having a pair of jaws adapted to receive a switch-blade between them, a spring plate on the outer side of one of the jaws, said jaws and spring having alined holes intermediate their ends, a rivet extending through said holes, said spring having ears engaging the adjacent jaw to prevent the spring from turning on the rivet, said jaws and spring also having another set of alined holes nearer their free ends, and a screw extending through said holes to receive a switch-blade, the underside of the screw being notched, said spring being formed with a projection adapted to enter said notches to prevent the screw from turning.
3. A switch clip having a pair of jaws adapted to receive a switch-blade between them, a spring plate on the outer side of one of the jaws, said jaws and spring having alined holes intermediate their ends, and a rivet extending through said holes and together with the spring determining the pressure of the jaws upon the switch-blade, one of said jaws being formed with an inwardly extending projection to limit the movement of the switch-blade and a pivot for the switch-blade independent of said rivet.
4. A switch clip having a pair of jaws adapted to receive a switch-blade between them, a spring plate on the outer side of one of the jaws, said jaws and spring having alined holes intermediate their ends, said spring having ears at one end bent to engage the edges of the adjacent jaw, and a rivet extending through said holes and together with the spring determining the pressure of the jaws upon the switch-blade.
5. In a knife-blade switch, the combination of a base plate, a clip and a support mounted thereon and each comprising a pair of jaws adapted to receive a switch-blade between them, a spring plate on the outer side of one of the jaws of the support and of the clip, said jaws and springs having

alined holes intermediate their ends to receive rivets and at their ends to receive screws, rivets extending through the holes therefor and together with the springs determining the pressure of the jaws upon the switch-blade, one of the jaws of the support and of the clip being formed with an inwardly extending projection to limit the movement of the switch-blade, and a screw extending through the holes therefor in the support, and a blade mounted on said screw.

6. In a knife-blade switch, the combination of a pair of similar blade receiving members each adapted to act as a support or as a clip, each formed with a pair of jaws and with a spring plate on the outer side of one of the jaws and with two sets of alined holes extending through the jaws and spring plate, a rivet extending through one of the sets of holes of each member and having one head on the outside of the spring plate so as to cause the jaws to be resiliently held toward each other, a screw extending through the other set of holes in one of the members, and a switch-blade mounted on said screw.

7. In a knife-blade switch, the combination of a pair of similar blade receiving members each adapted to act as a support or as a clip, each formed with a pair of jaws and with a spring plate on the outer side of one of the jaws and with two sets of alined holes extending through the jaws and spring plate, a rivet extending through one of the sets of holes of each member and having one head on the outside of the spring plate so as to cause the jaws to be resiliently held toward each other, a screw extending through the other set of holes in one of the members, and a switch-blade mounted on said screw, the head of said screw being formed with notches in its bearing surface and the spring plate being formed with a tooth which enters said notches and thereby secures the screw.

8. In a knife-blade switch, the combination of a pair of similar blade receiving members each adapted to act as a support or as a clip, each formed with a pair of jaws and with a spring plate on the outer side of one of the jaws and with two sets of alined holes extending through the jaws and spring plate, a rivet extending through one of the sets of holes of each member and having one head on the outside of the spring plate so as to cause the jaws to be resiliently held toward each other, a screw extending through the other set of holes in one of the members, and a switch-blade mounted on said screw, one of the jaws on each of said members being formed with a projection extending into the path of the switch-blade to limit its movement and prevent it from engaging said rivets.

9. A switch clip having a pair of jaws

- adapted to receive a switch blade between them, a spring plate on the outside of one of the jaws, said jaws and spring having aligned holes near their ends adapted to receive a screw or rivet for fastening the blade, means independent of the screw or rivet for fastening the spring to the jaw, and means to prevent the spring from turning out of alignment with the jaws.
- 10 10. A switch clip having a pair of jaws adapted to receive a switch blade between them, a spring plate on the outside of one of said jaws, said jaws and spring having aligned holes adapted to receive a screw, and a screw extending through said holes, said 15 spring plate and the head of the screw being provided with inter-engaging means to hold said screw from turning.
11. A switch clip having a pair of jaws adapted to receive a switch blade between 20 them, a spring plate on the outside of one of the jaws, said jaws and spring having aligned holes near their ends adapted to receive a screw or rivet for fastening the blade, and means independent of the screw 25 or rivet for fastening the spring to the jaws.

HARRISON J. L. FRANK.
